HANGER FOR DRESSES AND OTHER GARMENTS

Dorothy Jacob, Brooklyn, N. Y.

Application May 23, 1952, Serial No. 289,634

3 Claims. (CL 223—92)

1

The present invention relates to a new and highly useful hanger for dresses and other garments and more particularly to a hanger which is capable of receiving and holding various types and sizes of dresses and similar garments in a manner to enhance the display thereof and prevent such garments falling off the hanger.

Many garment and dress hangers have been heretofore designed of various constructions but these are subject to recognized disadvantages. For example, they are incapable of use in connection with garments of different types such as sleeveless dresses, dresses with scoop necklines, evening gowns and various dresses and blouses having low necklines or conventional necklines without such garments either falling off the hangers or being crushed or otherwise damaged as by being pierced by projecting points, which is especially important in connection with lace garments or garments having lace trim. Another disadvantage is that known hangers, even where they are provided with a single cut-out or recess on each hanger arm, are incapable of holding various types and sizes of garments and enabling them to be displayed so that they hang naturally and provide an attractive sales appeal. To a limited extent, this problem has been partially solved by providing garment hangers with clips or attachments but these have been found to be objectionable in use and not to provide the desired results and, consequently, so far as I am aware, there is no dress or garment hanger known or available which represents a satisfactory solution of the problem here involved.

One of the objects of my invention is to provide a dress or garment hanger which overcomes the disadvantages of previous hangers, which avoids the use of clips and attachments and which is constructed so as to be capable of receiving and holding dresses and garments of many different types so that they cannot fall off and are enhanced as to their appearance while on the hanger.

Another object of the invention resides in the production of a dress or garment hanger the oppositely extending arms of which are provided with a series of spaced indentations or cut-outs extending along a major portion of the upper edge of each such hanger arm, thereby providing a plurality or series of recesses for the receiving and holding of dresses and garments of different types, sizes and styles.

More specifically, an object of the invention resides in the production of a plastic hanger free from attachments and sharp projections which are capable of damaging dresses or garments

2

and wherein each of the oppositely extending arms of the hanger is provided along its upper edge with one single and three double cut-outs or indentations spaced longitudinally along the hanger arms and defined by extensions disposed in a generally longitudinal direction with relation to the hanger arms, certain of such extensions being arranged in sets or pairs so as to provide means for holding, without damage, dresses or garments of various types and styles while at the same time enabling them to be displayed in an attractive manner adding to their sales appeal and preventing such garments from falling off the hanger or being inadvertently dislodged from the hanger by handling of the hanger and/or the dress or garment.

Other and still further objects and advantages will be understood or appreciated hereinafter or will be pointed out below.

In the accompanying drawings:

Fig. 1 is a front elevational view of a hanger embodying my invention and showing thereon a dress or blouse having a low or wide neckline and wherein the garment is received and held in the outermost cut-outs or indentations of the hanger arms;

Fig. 2 is a view similar to Fig. 1 but showing a shallow or small neckline type of garment applied to the hanger and utilizing the innermost cut-outs or indentations of the hanger arms;

Fig. 3 is a view of my new hanger similar to Figs. 1 and 2 but showing applied thereto a garment having a deeper or wider V-type neckline and wherein the garment is received and held in the second cut-outs or indentations of the hanger arms;

Figs. 4 and 5 further illustrate my new hanger and the manner in which it is employed for skirts and garments of the shoulder strap type and showing how, by means of the new hanger construction, such garments are received and held in a manner which enables them to hang properly and naturally without stretching, distorting or crushing the garments and thereby adding to their display and sales appeal, such views showing the use of the second and third cut-outs or indentations of the hanger arms;

Fig. 6 is another side elevational view of my new hanger construction showing its use in connection with sleeveless dresses or gowns or evening gowns, or garments of such types and, as compared with Fig. 1, showing another use for the outermost cut-outs or indentations of the hanger arms.

Fig. 7 is an enlarged fragmentary detail of

one end of my new hanger with a plastic tube in place thereon.

Referring now to the drawings, my new hanger has a central body portion 10 which is preferably molded or otherwise formed from a transparent or translucent relatively heavy or thick synthetic plastic material such as Lucite but which may equally well be constructed of other materials such as wood, metals and alloys such as aluminum, stainless steel, chromium steel and other rust-resisting compositions, as well as other plastic materials, such as cellulose acetate, it being noted that I prefer to employ a plastic material or composition since the same lends itself particularly well to the invention, being relatively soft and free from surface irregularities or imperfections which could tear, pierce or otherwise damage the garments. In the further description of the invention, a hanger of plastic construction will be referred to for purposes of example with the understanding that the hanger may be made of any suitable material such as the other materials noted above.

A plastic hanger, as illustrated in the drawings, is so formed or molded as to provide a marginal rib or bead 11 which not only serves to enhance the appearance of the hanger but adds to its surface area, strength and durability. The central body portion 10 of the hanger is so formed as to provide the necessary apertures for the applying of the hook 12 which is swivelly mounted, as shown, and which is maintained in its proper relationship with respect to the central portion of the hanger by the enlargements 13 applied to the shank portion of the hook 12.

From the central body portion 10 of the hanger unitary plastic arms 14 extend in opposite directions and these are so designed that they have a smooth and gentle outward and downward curvature. Each such arm is provided along its upper edge with a series of longitudinally spaced cut-outs or indentations which extend along the major portion of the upper surface of each such arm and provide a series of garment-receiving and garment-holding recesses. The innermost cut-out or indentation 15 is single whereas, proceeding toward the distal ends of the arms, the cut-outs or indentations 16, 17 and 18 are double. These cut-outs or indentations, which may also be termed recesses, are formed in any suitable manner during or subsequent to the production of the hanger but in the case of a molded plastic hanger, which is preferred, the cut-outs or indentations 15 to 18 are made by suitably configuring the mold in which the hanger is produced. In the case of wood, for example, the cut-outs or indentations may be made by suitable saws, tools or machines and metal hangers may be made either initially as by stamping in the illustrated form or the cut-outs or indentations may be formed subsequently to the stamping or other mode of production of the hanger.

The cut-outs or indentations 15 to 18 are defined and delimited by means of a series of longitudinally spaced extensions certain of which, as will be noted, are arranged in sets or pairs. These extensions extend in the direction of the hanger arms and have a similar overall curvature. The extensions terminate either relatively close to the adjacent (underlying) portions of the hanger arms as in the case of the innermost cut-outs 15 or relatively close to one another as in the case of the outer cut-outs 16-18. The single cut-outs or indentations 15 are thus defined by the extensions 15' which provide a generally

U-shaped cut-out or indentation and the remaining cut-outs or indentations 16-18 are defined by extensions 16', 17' and 18' which are arranged in sets or pairs extending toward one another but terminating short of contact with each other so as to provide a relatively small opening or space therebetween, whereby the appropriate portion of the dress or garment can be inserted in the spaced cut-outs or indentations thus provided, and will be held snugly therein so as not readily to come out or fall off. The pairs of extensions 16', 17' and 18' also curve downwardly somewhat toward the hanger arms and taper somewhat without being objectionably pointed but terminate short of contact with the bottoms of the cut-outs or indentations so that garments can be inserted over the extensions into the cut-outs or indentations themselves with the extensions supporting the adjacent portions of the garments. The ends of the extensions are rounded and especially in the case of a plastic hanger are soft and therefore are incapable of damaging the garments or piercing the materials thereof.

The cut-outs or indentations 16, 17 and 18 are double, as compared to 15, and are of substantially U-shape and the outermost ends of the hanger arms are rounded and free from undesirable points or projections. It will, therefore, be understood that each hanger arm is provided with four U-shaped cut-outs or indentations of which the innermost are single and the others are double, but my invention is not to be construed as limited to the use of only four such cut-outs or indentations as other numbers thereof may be employed in modified forms of the invention but for best fulfilling the objects of the invention at least three such cut-outs or indentations should be provided since by so doing it is possible to accommodate garments of many different types, styles and sizes while still enabling such garments to be received and held by my new hanger without crushing or distorting the garments out of shape and therefore permitting them to hang naturally to add to the display and sales appeal thereof. My new hanger is extremely versatile in thus making provision for its use with garments of all different types, styles and sizes particularly with respect to necklines and the presence or absence of sleeves; consequently, the hanger is also well adapted for use with strap or halter-type garments and while to some extent the latter garments can be hung on known types of hangers they cannot be well-displayed while still enabling them to hang naturally and enhance their display and sales appeal. It will further be noted that in contradistinction to known hangers, it is not necessary to force garments into hanger recesses which are the wrong distance apart or which have projections or points which are apt to pierce or damage the material and this is especially true in connection with lace garments or garments trimmed with lace. My new hanger is therefore of superior design and construction and accomplishes results not hitherto possible with any previously known hanger.

For purposes of illustrating and demonstrating the versatility of my new hanger, the drawings show typical instances for the use of each of the plurality of U-shaped cut-outs or recesses. The wide, shallow neckline type of garment with sleeves is shown in Fig. 1 wherein opposite inner edges of the garment are disposed in the outermost indentations 18 over the end extension 18' and under the next adjacent extension

18'. In Fig. 2 a narrow neckline dress or garment is illustrated which is disposed under the innermost extension 15' and in the innermost U-shaped cut-out or indentation 15. In Fig. 3, a V-neckline type of dress or garment is illustrated wherein the inner edges thereof are inserted under the first extension 15' and within the U-shaped cut-out or indentation 15 and in this connection it should be further observed that the adjacent portions of the hanger are so shaped and configured as to resist movement of these garments from the hanger while holding them firmly but without damage between the extensions involved and the underlying adjacent hanger arm surfaces, and thus it has been found through actual use and test that garments do not fall off the hangers regardless of the position of the same and that the hangers can even be relatively roughly handled, shaken or turned upside down without the garments falling off or becoming dislodged. At the same time the hanger is so constructed that it in no way damages the garments by crushing, piercing, tearing or the like, and the garments at all times hang naturally as they would when worn so as to enhance their appearance and their display and sales appeal. In the case of Figs. 4, 5 and 6 various types of garments such as skirts and sleeveless or strap type garments are illustrated in use with my new hanger and it will be clearly apparent that, depending upon the particular type or style of garment and the size thereof, those cut-outs or indentations can be readily selected so that the garments also hang naturally with enhanced appearance and sales appeal.

It will furthermore be appreciated that my new hanger provides additional advantages which are of importance. Since garments do not come off the hangers until deliberately removed, numerous pressing and cleaning problems are eliminated and because the hanger does not damage the garments it is not necessary to repair them or to sell them at reduced prices. Consequently, my new hanger is of vastly superior construction and utility as compared with any prior type of hanger known to date and solves many problems in connection with the displaying and selling of dresses and other garments.

The foregoing is intended as illustrative not as limitative since, within the terms and scope of the appended claims, various modifications may be made without departing from the invention. For example, when very fine chiffon, lace or unusually thin or sheer dresses or garments are applied to my new hanger, I may place over the appropriate extensions, after the garment has been placed on the hanger, small pieces of rubber or

Vinylite or plastic tubing 19 (Fig. 7), preferably transparent, which not only positively prevent any possible damage to such dresses or garments but which add thickness to the extensions and frictional resistance against any movements thereof except those involved in their intentional or deliberate removal from the hanger. Such tubing also serves to lock the dress or garment in its position on the hanger, thereby eliminating all possibility of the dress or garment falling off the hanger.

I claim:

1. A garment hanger adapted to receive and hold all types of women's garments without damage thereto which comprises a plastic body portion with a pair of oppositely extending plastic arms unitary with the body portion, each of the plastic arms being provided along its upper edge with a series of cut-outs defined by arcuately-shaped, tapered extensions arranged in longitudinal alignment and having in-curved terminal portions close to but out of contact with adjacent portions of the hanger arms.
2. A garment hanger adapted to receive and hold all types of women's garments without damage thereto which comprises a plastic body portion with a pair of oppositely extending plastic arms, each of said arms being provided along its upper edge with a series of cut-outs defined by arcuately-shaped, tapered extensions arranged in longitudinal alignment and having in-curved terminal portions close to but out of contact with adjacent portions of the hanger arms.
3. A garment hanger adapted to receive and hold all types of women's garments without damage thereto which comprises a plastic body portion with a pair of oppositely extending plastic arms, each of said arms being provided along its upper edge with a series of cut-outs defined by arcuately-shaped, tapered extensions arranged in longitudinal alignment and having in-curved terminal portions close to but out of contact with adjacent portions of the hanger arms, at least one such extension of each hanger arm being covered with a piece of plastic tubing.

DOROTHY JACOB.
